UNITED STATES PATENT OFFICE.

KRISTIAN HARALD SMITH, OF COPENHAGEN, DENMARK.

ARRANGEMENT ON TALKING APPARATUS FOR THE RECEPTION AND REPRODUCTION OF RECORDS.

Application filed June 16, 1921. Serial No. 478,135.

To all whom it may concern:

Be it known that I, KRISTIAN HARALD SMITH, a subject of the King of Denmark, residing at Copenhagen, Denmark, have invented certain new and useful Improvements in an Arrangement on Talking Apparatus for the Reception and Reproduction of Records, of which the following is a specification.

10 This invention relates to a device which is designed to transfer the vibrations of mechanically operated diaphragms, e. g. of phonograph cylinders, gramophone disks or the like, to other diaphragms which are controlled by magnets.

15 The invention consists essentially in this, that the mechanically operated diaphragm transfers its vibrations to a second diaphragm. For this purpose the air enclosed 20 in the head of the talking machine can be utilized besides mechanical means for transmission. Magnets are arranged behind the second diaphragm whose vibrations generate feeble currents in the windings of these magnets. These feeble currents are then transferred to another magnet which on its part makes another diaphragm vibrate.

25 The vibrations of this latter diaphragm are therefore caused merely by the variation of the intensity of current in the magnets due to the vibrations of the first mentioned diaphragm, that is to say without the aid of any mechanical means. No battery needs to be inserted in the circuit. Very 30 clear tones are consequently produced by this diaphragm so that the conversations recorded on the phonograph cylinder or on the gramophone disk are reproduced distinctly.

35 40 The arrangement can be further made in such a manner that this electrically operated diaphragm is not mounted in the same casing as the others but at any other place, e. g. directly in the receiver head.

45 In order that the invention may be clearly understood, I shall proceed to describe the same with reference to the several forms given by way of example in the accompanying drawing, wherein:—

50 Fig. 1 shows the diaphragms combined in one casing.

Fig. 2 illustrates the arrangement according to which the receiver diaphragm is separated from the transmitting diaphragm.

55 Fig. 3 shows diagrammatically a connec-

tion with condensers for the clearest possible reproduction of the sounds.

The casing *a* of the talking head is divided into two separate parts by a partition *b*. At either side of the partition *b* an annular steel magnet *c* or *d* respectively with pole-pieces *g* or *h* is arranged. The coils are connected to one another by spring *l* and the contacts *m*. The diaphragms *n* and *o* are mounted in front of the coils *g* and *h* respectively. When the diaphragm *n* vibrates it produces an electric current in the closed circuit *l* through which the diaphragm *o* is attracted. The diaphragm *n* is operated from the diaphragm *p* whose pin *r* is in the well known manner in contact with the phonograph cylinder *s*.

The vibrations of the diaphragm *p* can be transmitted to the diaphragm *n* either by mechanical means or by the air enclosed in the head *a* of the talking machine. The vibrations of a mechanically operated diaphragm are thus transferred to a second diaphragm which itself operates a third diaphragm by electric currents.

The apparatus described can also be used as receiver when the switches are reversed so that the contact at *m* is interrupted, the contact at *t* being closed. If in this case a person speaks into the microphone *u* which may be arranged at any convenient point, the diaphragm *n* will be vibrated by the variation of intensity of current in the wire *v* and the diaphragm *n* will transmit its vibrations to the diaphragm *p*. The reception can be made from any distance. For the reproduction of the conversations recorded on the cylinder *s* the receivers *w* are used which are connected with the diaphragm *o* by a tube.

In the form of construction shown on Fig. 2 the talking head *a* comprises only the diaphragms *p* and *n*. The diaphragms *o* which are to be operated from diaphragm *n* by means of magnetic currents are mounted in the receivers *x*. A condenser *z* can be inserted in the circuit *y* of the receivers. This arrangement has the advantage that noises produced by the revolving of the cylinder *s* and by the driving of the same are not transferred to the receivers. Experiments have shown that a very clear and distinct reproduction of the communication is obtained.

According to Fig. 3 two condensers 1 and 2 are inserted in the circuit.

The condenser 2 is inserted in the wire 3 between the two magnets *g* and *h*, the condensers 7 being mounted in a connecting wire 4. This arrangement ensures also a clear and distinct reproduction of the communications received.

The constructional details can be modified according to requirement.

The essential feature of the invention is 10 the transfer of the mechanically produced vibrations of the receiving diaphragm to the reproducing diaphragm by electricity.

I claim:—

1. The combination of a diaphragm, a second diaphragm, mechanical means for transmitting the vibrations of said first-named diaphragm to said second-named diaphragm, a magnet electro-magnetically co-acting with said second-named diaphragm, a 15 third diaphragm, a magnet co-operating with said third-named diaphragm, an electrical circuit interconnecting said magnets, a microphone and switching means for connecting said microphone with said first-named magnet while disconnecting said first-named magnet out of circuit with said second-named magnet.

2. The combination of a reproducing diaphragm, a second diaphragm, mechanical 30 means interconnecting said first-named and said second-named diaphragms to transmit vibrations from one to the other, a magnet in magnetic relation with said second-named diaphragm, a third diaphragm, electro-magnetic means controlling said third-named diaphragm and an electrical circuit inter- 35 connecting said magnet and said electro-

magnetic means, said electrical circuit including a condenser.

3. The combination of a reproducing diaphragm, a second diaphragm, mechanical 40 means interconnecting said first-named diaphragm and said second-named diaphragm to transmit the vibrations of one to the other, a magnet in electro-magnetic relation 45 with said second-named diaphragm, a third diaphragm, a magnet controlling the vibrations of said third diaphragm, an electrical circuit interconnecting said first-named and said second-named magnets, a microphone 50 connected to said electrical circuit and switching means for interconnecting said microphone in circuit with said first-named magnet.

4. The combination of a reproducing diaphragm, a second diaphragm, mechanical 55 means interconnecting said first-named diaphragm and said second-named diaphragm to transmit the vibrations of one to the other, a magnet in electro-magnetic relation 60 with said second-named diaphragm, a third diaphragm, a magnet controlling the vibrations of said third diaphragm, an electrical circuit including a condenser interconnecting 65 said first-named magnet and said second-named magnet, a microphone and switching means for connecting said microphone with said first-named magnet while disconnecting said first-named magnet out of circuit with 70 said second-named magnet.

In testimony whereof I affix my signature.

KRISTIAN HARALD SMITH.
